LAMP CONNECTION

Henry H. Harris, Detroit, Mich.

Application May 23, 1930, Serial No. 454,956

12 Claims. (Cl. 173—328)

This invention relates to electrical connections and contacts for stand lamps of the floor or table type and has for its object to provide contacts of this type which are normally hidden from view and which preclude the use of loose or free wires running promiscuously over a portion of the room in which the lamp is located.

A specific object of the invention is to provide an electrical terminal carrying means which may be placed beneath a rug, scarf or mat for engagement with contacts in the base of a lamp and to provide proper piloting means for centering the contacts of the lamp directly over the contacts beneath the rug, it being understood that a hole in the rug or scarf is provided for permitting a direct connection.

A further object of the invention is to provide a pilot means for the purposes described which will not only serve as a guide for centering the lamp but which will require that either a very small hole be pierced in the rug, or in some cases no hole at all.

A still further object of the invention is to provide a contacting means beneath the rug which will be invisible or substantially so at such time as the lamp may not be in position thereof and to provide retractable contacts carried by the base of the lamp which may be lowered and retracted either manually or automatically in order to make and break a circuit through the lamp when desired and in order to protect the contacts by retraction during such times as they may not be in a propitious position for exposure.

I am aware that attempts have previously been made to provide hidden connections for floor lamps but the objections heretofore met with reside in the fact that there was either no proper piloting means, or electrical contacts which were more or less pointed extended permanently through the rug and thereby were subject to damage due to the fact that anyone walking on the rug was liable to step on them and, therefore, bend them over. Another drawback to permanent upstanding contacts is that they are easily short-circuited and hence comprise a constant fire hazard. The present invention seeks to overcome such difficulties by the provision of the arrangements revealed in the drawings and described herein, as will now be referred to in detail, with reference to the accompanying drawings wherein in several embodiments are illustrated by way of example and in which:

Figure 1 represents a conventional carpet or rug having the contact carrying plate schematically shown therebelow and the lamp schematically ele-

vated thereabove prior to the meshing of the parts;

Figure 2 is a vertical section taken centrally of Figure 1 with the parts assembled;

Figure 3 is a detail view of a modification of a 60 socket.

Figure 4 is a further modification of the device shown in Figure 3;

Figure 5 is a vertical section of a modification of the invention as revealed in Figure 2; and 65

Figure 6 is a vertical section of a still further modification of Figures 2 and 5.

Referring more particularly to the drawings, numeral 1 refers to a conventional rug or carpet having a plate or pad 2 therebeneath into which 70 electrical lines 3 terminate into conductor rings 4. Centrally of the plate or pad 2 is an upstanding post 5 pointed at its end and threaded for a distance. The pad 2 is adapted to be placed underneath a rug in such a way that the post 5 extends 75 upwardly through a hole in the rug for this point at the place where the lamp is desired to be used. Above the conductor rings 4 further holes do not need to be provided, as will now be described.

6 refers to the base of a floor lamp having terminals 7 retractably mounted therein by a simple manual leverage arrangement 8. This base may be of wood or other insulating material, or it may be of metal, in which case the contacts can be insulated by any familiar means. Upon depression 80 of the lever or pedal 8 the terminals 7 which are quite small and preferably rounded at the ends are depressed through a carpet until they contact the rings 4. Since a carpet is generally 85 more or less loosely woven, the terminals 7 readily 90 pass between the threads thereof and do not damage the carpet even after having pierced it many times. Centrally of the bottom of the base of the lamp is a circular opening 9 adapted to receive 95 a ball 10 which acts as a guard for the point of the post 5 thereby centering the lamp with respect to the pad 2. The ball 10 is left over the post 5 at all times regardless of whether or not the lamp may be in position. Thus if there is no 100 lamp above the pad 2 the ball 10 acts as an indicator for the location of the pad and protects anyone walking on the carpet from injury from stepping on the post. A suitable locking means 105 may be employed, if desired. In positioning the lamp above the contacts, it is only necessary to see that the ball 10 finds its way into the opening 9 and as soon as this shall have been accomplished, the contacts 7 are automatically positioned over the rings 4 and the lamp may be 110

electrically connected to the line 3 merely by depression of the pedal 8.

- While these rings 4 may be flat, it is sometimes best to provide a positive engagement such as may be had by the crimped ring 4' shown in Figure 3 or by the spring ring as shown at Figure 4 at 4''. In Figure 5 the carpet is indicated at 11 and the terminal carrying plate at 12. In this form two retractable plugs 13 carrying terminals 14 extend through the base of the lamp as shown for depression through the rug 11 for the purpose of establishing the necessary contact. The center 15 of the plate 12 is elevated for the purpose of acting as a pilot for the base of the lamp in order to guide the terminals 14 to a position directly over the terminals carried by the base 12 prior to depression into electrical engagement therewith. With piloting means such as shown by this figure, no hole need be provided in the carpet. In Figure 6 the same type of base plate 12' is illustrated as is shown in Figure 5. According to this form, the contacts 16 are pivotally carried by links 17 which are in turn pivotally mounted interiorly of the base of the lamp and which are acted upon by springs 18 for the purpose of maintaining the contacts 16 in a normal retracted position interiorly of the base of the lamp. As the central portion 15' of the base 12' finds its way into the center cavity 19, this high point 15' not only acts as a pilot for centering the contacts 16 over the terminals in the base 12, but elevates the inner ends of the links 17 against the springs 18 thereby establishing electrical contact necessary to complete an electric circuit through the lamp by causing the depression of the terminals 16.

It will be seen from the foregoing that numerous modifications and various combinations may be made without departing from the spirit of my invention and I, therefore, desire to be limited in the construction and application thereof only by the scope of the appended claims.

What I claim is:

1. The combination of a stand lamp having electrical contacts mounted in the base thereof and depressible and retractable relative thereto and a base plate having terminals connected to a source of electric energy, said electrical contacts in the base of the lamp being depressible for establishing contact with said terminals to establish a circuit through said lamp.

2. The combination of a stand lamp having electrical contacts movably mounted in the base thereof, a member having a surface upon which said lamp rests, terminals connected to a source of electric power on said surface, and pilot means on said member cooperating with the base of the lamp for guiding the contacts of said lamp to a position directly over said terminals, and means for depressing said contacts after the lamp is positioned by the pilot means to establish electrical engagement with said terminals.

3. In combination, a stand lamp having a base, said base having a central cavity therein and depressible and retractable electrical contacts mounted on said base laterally of said cavity, a plate situated beneath said lamp carrying terminals connected to a source of electric energy, upstanding means carried by said plate extending into the cavity of said base to align said contacts and said terminals, and means for depressing said contacts relative to the base to establish an electrical engagement with said terminals.

4. In combination, a stand lamp having a base, said base having a central cavity therein and

retractable electrical contacts laterally of said cavity, a plate situated beneath said lamp carrying terminals connected to a source of electric energy, upstanding means carried by said plate, a guard for said upstanding means adapted to closely engage the cavity in the base of said lamp and to protect said upstanding means when the lamp is removed, said guard comprising a pilot for aligning said contacts and said terminals, preliminary to depressing said contacts into engagement with said terminals.

5. In combination, a stand lamp having a base, said base having a central cavity therein and retractable electric contacts laterally of said cavity, a plate situated beneath said lamp carrying ring terminals connected to a suitable source of electric energy, upstanding means on said plate centrally of said ring terminals, said means extending upwardly into the cavity of said plate for aligning the contacts in the base of the lamp directly over some point on the ring terminals, and means for depressing said contacts into engagement with said rings.

6. In combination, a plate having ring terminals connected to a suitable source of current adapted to be placed under a cover such as a rug, said plate having an upstanding portion centrally of said rings, a lamp having a base equipped with retractable contacts above said rug, the base of said lamp being provided with a central cavity, the center of said cavity being spaced from said contacts a distance equal to the distance from the center of said upstanding portion of the plate to said rings, said upstanding portion projecting into said cavity to align said contacts over said rings, and means for depressing said contacts through said rug to establish an electric circuit from said terminals through said lamp.

7. In combination, a plate equipped with ring terminals adapted to be placed under a cover such as a rug, an upstanding post on said plate centrally of said rings extending through the rug, a guard for said post, a stand lamp having a base equipped with retractable electrical contacts, the base of said lamp having a central cavity at a distance from said contacts equal to the distance of said post from the terminals of said plate, the guard on said post being adapted to closely fit the cavity of said lamp to align said contacts and said ring terminals, and means for depressing said contacts through said rug to engage said terminals.

8. In combination, a plate equipped with ring terminals adapted to be placed under a cover such as a rug, an upstanding notched post on said plate centrally of said rings extending through said rug, a guard for said post above said rug, means for locking said guard to the notches on said post, a stand lamp having a base equipped with retractable electrical contacts, the base of said lamp having a central cavity at a distance from said contacts equal to the distance of said post from the terminals of said plate, the guard on said post being adapted to closely fit the cavity of said lamp to align said contacts and said ring terminals, and means for depressing said contacts through said rug to engage said terminals.

9. In combination, a stand lamp having a recessed base, a member adapted to be disposed below a cover, and having a pin projecting through the cover, centering means removably connected to said pin and adapted to be received into the recess in said base to center the lamp stand, and contacts on said base and said mem-

ber adapted to engage in the centered position of the member and the stand lamp.

10. In combination, a plate having ring terminals adapted to be connected to a source of power, said plate having an upstanding portion centrally of said rings, a lamp having a base provided with a recess adapted to receive said upstanding portion to center the lamp on the plate, and contacts mounted in said lamp base and depressible and retractable with respect thereto located to align with the ring terminals in the centered positions of the lamp.

11. In combination, a plate adapted to underlie a rug or the like and having flat electric terminals

15

nals thereon and having a central substantially unyielding projection thereon, a stand lamp having a central recess in the under side of its base, contact points for the lamp movably mounted in the base, and lever mechanism extending into the recess in the base and connected with the contact points whereby the contact points are forced downwardly from the base when the stand lamp is placed with its recess over the projection on the plate.

12. The device of claim 11 in which the terminals are rings concentric with the projection on the plate.
